UNITED STATES PATENT OFFICE

162,116

TRACTOR CAB OR THE LIKE

Frederick Harold Barton, Bounty, Saskatchewan,
Canada

Application June 14, 1950, Serial No. 10,519
In Canada January 16, 1950

Term of patent 14 years

(Cl. D14—3)

To all whom it may concern:

Be it known that I, Frederick Harold Barton, a citizen of the Dominion of Canada, and resident of Bounty, in the Province of Saskatchewan, Dominion of Canada, have invented a new, original, and ornamental Design for a Tractor Cab or the like, of which the following is a specification, reference being had to accompanying drawing, forming part thereof.

Fig. 1 is a front perspective view of a cab for a tractor showing my new design; and

Fig. 2 is a rear perspective view thereof.

I claim:

The ornamental design for a tractor cab or the like, as shown.

FREDERICK HAROLD BARTON.
